UNITED STATES PATENT OFFICE.

SIDNEY A. SASSAMAN, OF PENNS CREEK, PENNSYLVANIA.

CRANK-CASE SUPPORT.

Application filed May 24, 1924. Serial No. 715,676.

This invention relates to improvements in automobile engine supports, and particularly to hangers or supports adapted to be used in the repair of motor vehicles where the 5 crank case hanger proper has been broken off or otherwise injured so that it does not function properly.

One of the objects of the present invention is to provide a very effective, simple and 10 strong repair hanger or support for the crank cases of Ford cars which may be readily put in place where the ordinary hanger or crank case of a Ford car has been broken off.

15 A further object is to provide a device of this character which is formed in two parts, with means whereby these two parts may be drawn together so as to thereby secure full support for the engine and transmission case.

20 A still further object is to provide a device of this character which is rigidly attached to the frame of the automobile, and which may be readily put in place or readily 25 disengaged.

My invention is illustrated in the accompanying drawing, wherein: —

Figure 1 is an end elevation of the lower portion of a crank case and the brackets therefor, the frame of the automobile being shown in section and illustrating my improved crank case and transmission support mounted upon the frame beams;

Figure 2 is an enlarged vertical sectional view through one frame beam of the machine, the usual hanger and my improved support.

Figure 3 is a fragmentary perspective view of the flange 17 at the lower end of section 16;

Referring to this drawing, 10 designates one of the channel iron frame bars of a Ford automobile. The crank case 11 is normally supported upon these frame bars by means 45 of oppositely disposed brackets, each bracket being formed of relatively thick sheet metal bent at its upper ends so as to extend over the top of the channel iron, as at 12, extend downward on the inside of the channel iron, and then outwardly deflected, as at 13, and formed with a relatively wide flat portion which bears against and is riveted or bolted to the crank case. The downwardly extending portion 12^a of the bracket is so formed 50 that its outer face, or that face confronting

the channel iron, is provided with a shallow channel 12^b.

These hangers usually break at the point 60 a. These hangers are also ordinarily formed with two laterally disposed, relatively heavy beads 14. The hangers are bolted to the crank case by a transverse bolt 15 which passes through each hanger and to the outside of the channel iron. So far I have described the ordinary Ford hanger. 65

The repair hanger or support which I have devised, however, is designed to be used permanently in case of the breakage of the regular hanger, and this hanger consists of two relatively wide bands of sheet 70 metal 16, these bands being bent to conform approximately to the shape of the bottom of the crank case, the lower ends of these bands being outwardly deflected, as at 17, and having bolt holes through which a pair of bolts 75 18 pass. When this device is in place upon a crank case, these bolts 18 embrace the regular drain plug of the crank case. That portion of the band 16 confronting the outer face of 12^a of the hanger lies within the 80 channel 12^b of this section so that the hanger occupies its normal position with relation to the channel iron when the straps 16 are in position. By engagement of the straps in these channels deflection of the straps with 85 relation to the hanger is prevented.

The upper end of each of these bands or sections 16 is angularly bent, as at 19, so as to engage over the lower flange of the channel iron 10. Disposed upon the outer face 90 of the channel iron frame is a brace 20, the upper end of which extends vertically upward against the outer face of the channel iron, while the lower end extends downward parallel to the face of the band section 16 95 and is bolted thereto by a bolt 21.

Disposed within the channel iron 10 and approximately filling this space is a wooden block 22 having a depth equal to the depth of the channel iron and through which 100 passes a bolt 23, this bolt passing through the channel iron, through the ordinary hanger, and through the upper end of the brace 20, this bolt carrying nuts, as usual. The upper end of the block 22 is cut away at 24 105 so as to accommodate the nut 25 on the ordinary bolt 26 which passes through the upper end 12 of the regular hanger. Preferably the lower end of each strip is outwardly bulged at its middle between the perfora- 110

tions 17 so as to strengthen the angular bend and prevent the strain flattening this bent out.

It will be seen that this repair hanger is 5 very simple and it connects on to the frame on both sides of the frame. Whether the hanger has broken off at the corner *a*, as before described, or whether the hanger is entirely removed where the hanger is broken 10 off, the bolt holding the hanger to the frame may be released and the strap or supporting band 16 passed up between the crank case and the frame and hooked upon the lower flange of the frame. Then the wooden block 15 may be put in place and the bolt passed through the upper end of the bracing strap 20, through the wooden block 22, and through the hanger. The bolt may be then passed through the lower portion of the 20 bracing strap 20 and the supporting strap 16. After the two sections are put in place, the bolts 18 may be passed between the sections and tightened up until the supporting straps 16 are firmly engaged with the crank 25 case.

It will be seen that the block 22 when in position holds the angular end 19 of the supporting strap 11 in place upon the lower flange of the channel iron and prevents any 30 possible dislodgment of the supporting strap 11 with relation to the channel iron. It will be seen that these hangers can be put on a Ford car or a Ford truck before the crank case arms or hangers are broken off, thus 35 safeguarding or reinforcing the car. The arm, as before remarked, generally breaks off at the point *a*, and the upper portion of the hanger is left on just as it was when the new hanger is put in place. Then the 40 engine is drawn up in place, the old hanger keeps the engine from jumping up and holds it tight, and keeps that part of the new hanger which fits on the inside of the frame from coming off.

I do not wish to be limited to the exact 45 construction of this crank case supporting device as I have described it in detail, as obviously some of the details might be varied without departing from the spirit of the invention.

50 I claim:—

The combination with an engine crank case and supporting means therefor comprising parallel channel irons having their channels inwardly directed, the channel irons being arranged at opposite sides of the engine base, the base having upwardly projecting hangers confronting the channel face of the channel irons and having at their upper end portions engaging the upper surface of the 60 channel irons, of means for additionally supporting the crank case including a support extended beneath the engine, and having at its ends upwardly extending portions extending between adjacent faces of the channel irons and their associate hangers, the upper ends of the support being outbent and resting upon the upper surfaces of the lower flanges of the channel irons, a filling block 65 tightly engaging between the upper surface 70 of the outbent portions and the confronting face of the upper flange of each channel iron, and a securing element for attaching together each yoke and its channel iron extending through the corresponding filling 75 block to prevent movement thereof, and supplemental braces having their upper ends fitting against the outer faces of the channel iron and the lower faces fitting against the outer faces of the support adjacent the ends 80 thereof and secured thereto, said securing element for the hanger serving as a means to secure the upper ends of the supplemental braces to the channel irons.

85 In testimony whereof I hereunto affix my signature.

SIDNEY A. SASSAMAN.
